UNITED STATES PATENT OFFICE.

JOHN C. BRADLEY AND TRUMAN H. GILBERT, OF BUFFALO, NEW YORK,
ASSIGNORS TO PRATT & LETCHWORTH COMPANY, OF BUFFALO, NEW
YORK.

MOLDING-MACHINE.

SPECIFICATION forming part of Letters Patent No. 715,964, dated December 16, 1902.

Application filed February 10, 1902. Serial No. 93,302. (No model.)

To all whom it may concern:

Be it known that we, JOHN C. BRADLEY and TRUMAN H. GILBERT, citizens of the United States, and residents of Buffalo, in the county 5 of Erie and State of New York, have invented new and useful Improvements in Molding-Machines, of which the following is a specification.

This invention relates more particularly to 10 a molding-machine in which a vertically-movable mold-table is provided, above which is arranged a frame carrying a device for pressing or ramming the mold and a device for drawing the pattern from the mold, said 15 frame being movable to bring either the ramming device or the pattern-drawing device into operative position over the mold-table.

The object of the invention is to provide a 20 machine of this character of very simple and desirable construction, in which the mold can be rapidly formed and the pattern removed quickly without injuring the mold.

In the accompanying drawings, consisting 25 of three sheets, Figure 1 is a side elevation, partly in section, of a molding-machine embodying the invention and showing the presser in operative position over the mold-table. Fig. 2 is a front elevation, partly in 30 section, of the machine, showing the pattern-drawing device in operative position over the mold-table and connected to the pattern for drawing the same. Fig. 3 is a plan view of the machine. Fig. 4 is a vertical sectional 35 elevation through the pattern drawing and ramming devices. Fig. 5 is a sectional view through the controlling-valve for the operating-cylinder for the mold-table. Fig. 6 is a similar view of the valve controlling the 40 drawing and ramming cylinders. Fig. 7 is a fragmentary sectional elevation showing the presser-frame about to be swung under its holding-spring.

Like letters of reference refer to like parts 45 in the several figures.

A represents a base-plate of any suitable form and adapted to be affixed to some suitable foundation; B, an upright or standard rising therefrom, and C a bearing-bracket 50 which is adjustable vertically on the stand-

ard by suitable means—such as upper and lower collars c, surrounding the standard—which is preferably cylindrical and provided with set-screws c', passing through the collars and bearing against the standard. The 55 upper end of the bearing-bracket extends forwardly from the standard and is provided at its front end with a vertical bearing D, which constitutes a guide for the mold-table in its vertical movement. 60

E represents the mold-table, which may be of any suitable form adapted to support a mold-blank of the usual well-known type, the table being shown in the form of a flat board or plate which is carried by the upper 65 end of a vertical stem e, which slidably engages in a vertical opening in the bearing D. The table is raised and lowered, preferably, by a fluid-operated means of any suitable construction. In the construction shown the 70 lower end of the stem e, carrying the mold-table, is connected to the upper end of a bottomless cylinder F, which surrounds and slides on an inner cylinder f, which at its lower end is secured rigidly to the base-plate 75 and is open at its upper end. This arrangement of the cylinders prevents any sand which falls from the mold-table from getting on the bearing-faces of the cylinders.

G represents a supply-pipe for fluid under 80 pressure, preferably compressed air, which is connected by a branch pipe g to the lower end of the inner cylinder f. The branch pipe is provided with a controlling-valve g', preferably a three-way cock. When the three-way cock is in one position, the supply-pipe communicates with the branch pipe and compressed air is admitted to the inner cylinder, which causes the outer cylinder and stem to lift the mold-table. When the cock is turned 85 to another position, the branch pipe is connected with an exhaust-opening g² in the valve-casing and the upper cylinder and table are permitted to lower or fall. The mold-table is preferably connected to the upper 90 end of the stem by means of a universal ball-and-socket joint H. The joint-socket, which is secured rigidly to the under side of the mold-table, is provided at its lower end with a plane or horizontal rim h, which when the 100

mold-table is lowered rests flat upon the upper horizontal face of the bearing D and causes the mold-table to assume a horizontal position in the event of the same being tilted or inclined when the cylinder is raised. The socket fits the ball sufficiently tight to hold the mold-table horizontally, unless the mold is forcibly moved out of its horizontal position.

5 I represents a gage-strip, which is preferably detachably and adjustably secured on the upper surface of the mold-table at the rear thereof by any suitable means, such as clamps i. This strip forms a stop against which the mold-flask can be placed to insure the correct 15 position of the same on the mold-table.

J represents the pressing or ramming device. It is preferably a flat plate secured horizontally to the under side of one end of a frame K, which is swiveled on the upper portion 20 of the vertical standard B, so as to swing horizontally to carry the pressing device to or away from a position vertically over the mold-table. In the construction shown the frame is provided with a central vertical bearing-sleeve, which loosely surrounds the standard and rests on a collar k, which surrounds the standard below the frame or arm and is adjustably secured to the standard by means of set-screws k', passing through the collar and bearing against the standard. The frame 25 can swing about the standard on the collar, and to reduce friction bearing-balls k² are arranged in grooves in the upper face of the collar and lower face of the bearing-sleeve.

30 35 k³ represents a collar secured to the standard above the frame to prevent upward movement of the frame when the mold is raised against the pressing device. By means of the adjustable collars k and k³ the frame can be 40 adjusted to any desired distance above the mold-table to accommodate different-sized flasks for different classes of work.

45 k⁴ represents a spring secured at its upper end to a collar k⁵ at the upper end of the standard and having its lower end extending down in a position to engage yieldingly on the upper face of either arm of the swinging frame when the same is swung beneath the spring. The side edges of the frame-arms or the spring, 50 or both, are beveled, as indicated in Fig. 7, so that when one of the arms engages the spring it is strained slightly and bears on the arm with sufficient force to hold the frame from swinging. The spring acts to hold the arm of the frame centrally over the mold-table.

55 The device for drawing the pattern from the mold is carried at the end of the swinging frame K opposite to that at which the pressing-plate is located and is constructed 60 as follows:

L represents a hollow tube or sleeve which is vertically movable in a guide-bearing l, provided therefor at the end of the frame and which is provided at its lower end with 65 a chuck, which is adapted to take hold of a part secured to the pattern.

m represents a chuck-stem which is ar-

ranged vertically in the hollow drawing-sleeve and is provided at its lower end with an enlargement m', which is split or divided 70 to form jaws and is provided with an external conical face, which coöperates with an internal conical face m² in the lower end of the sleeve L. The lower split end of the chuck-rod is provided with a conical cavity m³, in 75 which is adapted to engage a conical pin N, secured to the pattern. In practice the patterns are provided with said conical pins, which may be secured in any suitable manner—for instance, by screwing the same into 80 screw-threaded holes in the patterns. The chuck-stem extends upwardly through the upper end of the drawing-sleeve and has pivoted thereto an operating-lever O, which is provided with a cam-shaped or eccentric portion O' at its end which bears on the top of the sleeve. When the outer end of the lever is swung upwardly, this eccentric portion bearing upon the upper end of the drawing-sleeve raises the chuck-stem relative to the 85 sleeve, tightly wedging the chuck-jaws in the conical end of the drawing-sleeve, which causes the jaws to clamp tightly on the conical pin N, secured to the pattern.

O² represents a hook secured to a collar O³ 95 on the upper end of the drawing-sleeve adjacent to the inner end of the lever and adapted to engage with a shoulder O⁴ on the lever when the latter is turned or swung downwardly. When the shoulder engages the 100 hook, the pivotal movement of the lever is opposed, and further downward pressure of the lever will force the chuck-stem downwardly to open its jaws to release the pattern-pin.

105 The fluid-operated mechanisms for raising the drawing-sleeve to draw the pattern from the mold and for rapping or vibrating the drawing mechanism to loosen the pattern in the mold are preferably constructed as follows:

P represents a cylinder for the fluid-operated rapping device or piston. It is rigidly secured to the end of the swinging frame adjacent to the bearing for the drawing-sleeve, 115 as by a bracket p, secured to the lower end of the bearing and projecting laterally beneath the cylinder P. The cylinder P serves as a support for the drawing-cylinder Q, which is secured to the top of the cylinder P 120 and preferably has an open upper end. An open-bottomed cylinder q surrounds and slides vertically on the drawing-cylinder and is provided at its lower end with a lateral arm q', secured to the collar O³, in which the 125 drawing-sleeve is vertically adjustable, as by set-screws q². This adjustable connection between the drawing-sleeve and its operating-cylinder enables the former to be set nearer to or farther from the mold-table to 130 facilitate its use with mold flasks or patterns of different heights.

R represents a pipe which leads to the cylinder of the rapping device, and r a branch

pipe leading therefrom to the lower or inner drawing-cylinder. The pipe R is supplied with fluid under pressure, preferably compressed air, by a flexible hose r' , connected 5 to the supply-pipe G and to the pipe R. At the juncture of the branch pipe r with the pipe R is a valve r^2 , Fig. 6, preferably a three-way cock, which controls the passage of the compressed air to both the drawing-cylinder 10 and the cylinder of the rapping device.

The rapping device may be of any suitable construction in which a piston or the like is adapted to be rapidly reciprocated or vibrated by fluid-pressure. In the construction shown 15 in Fig. 4 a piston p' is mounted in the cylinder P and adapted to reciprocate therein and strike at its opposite ends against hardened-steel anvils p^2 , secured in the opposite ends of the cylinder. p^3 p^4 represent ports leading 20 from the fluid-pipe R to the opposite ends of the cylinder, and p^5 a sliding valve which controls said ports. p^6 represents a lever pivoted in an opening in the side of the cylinder and having one end projecting into a slot in 25 the piston and having the other end projecting into a slot in the valve, the construction being such that when the piston is moved in one direction the valve is moved positively. p^7 p^8 represent exhaust-ports leading from the 30 cylinder. When the piston is in its lower position, (shown in Fig. 4,) the valve is raised, and when the three-way cock r^2 , controlling the supply-pipe, is turned to open the pipe R compressed air enters the port p^4 and the 35 cylinder beneath the piston, raising the same until the exhaust-port p^8 is uncovered and permits the escape of the compressed air. The upward movement of the piston shifts the valve, so as to close the inlet-port p^4 and 40 open the inlet-port p^3 , thus admitting air to the upper end of the cylinder and driving the piston down until the upper exhaust-port p^7 is uncovered. Thus the piston is caused to 45 reciprocate rapidly, striking at its opposite ends against the anvils and causing a vibration of the pattern-drawing device. The ports of the three-way cock are so arranged that when the same is turned slightly from the position indicated in Fig. 6 the air is first 50 admitted to the rapping-cylinder and the rapping device put into operation. By turning the cock slightly farther air is admitted through the branch pipe to the drawing-cylinder, which causes the outer cylinder q to 55 rise and lift the drawing-sleeve and pattern attached thereto. While the pattern is being drawn or moved upwardly out of the mold it is at the same time being rapped or vibrated to prevent any possibility of the pattern 60 breaking the mold. The drawing-sleeve is guided and held in a true vertical line by its guide-bearing. The air may be exhausted from the cylinder q in any convenient way to permit it to lower. For instance, the cylinder is provided with a small hole q^3 , Fig. 4, 65 which is covered by the lower cylinder Q, ex-

cept when the upper cylinder q is in its highest position.

S represents a spring secured at its upper end to the collar O³, to which the drawing-sleeve is secured, and extending downwardly beside the bearing for the drawing-sleeve. When the latter is raised to its upper position, (indicated in Figs. 1 and 4,) the lower end of the spring snaps inwardly on the top 70 of the bearing and holds the drawing-sleeve raised until the spring is disengaged from the top of the bearing. The drawing-sleeve is thus held up while the pattern is released from the chuck. 80

T represents a conical shield which is secured to the under side of the mold-table and surrounds the ball-and-socket connection between the stem and the table. The hood is provided with a lateral extension t, which 85 projects rearwardly toward the standard over the bearing-bracket. Preferably a supplemental substantially V-shaped shield t' straddles the top of the bearing-bracket beneath the shield extension. These shields effectually prevent any sand which falls from the mold-table from getting on the bearing-bracket and into the bearing for the sliding stem. The cylinders for lifting the table are also preferably provided with an inclosing 90 casing t², which prevents the sand from coming into contact with the bearing-surfaces of the cylinders. 95

The operation of the machine is as follows: A pattern which has been provided with a 100 conical drawing-pin, as above explained, is placed on the match section or board U of the mold, with the drawing-pin extending downwardly, as shown in Fig. 1. One section u of the mold flask is then placed on the 105 match and sand filled in the same around the pattern. The sand is roughly smoothed off, and the operator then turns the three-way cock g' in the supply-pipe for the table-operating cylinder so as to admit compressed air 110 to the latter. The table is thus raised and the mold-section, with the sand therein, carried up against the under face of the pressing or ramming plate, which presses the sand in the flask-section, forming the nowel or one 115 part of the mold. After the first part of the mold has been pressed, the three-way cock is turned to connect the branch supply-pipe with the exhaust-opening, which permits the air to escape from the cylinder and the mold-table to drop to its lower position. (Indicated in Fig. 1.) A bottom board u' is now 120 placed on the nowel and the latter and match inverted by the operator and the match lifted off of the nowel. Parting sand is then sprinkled on the upper surface of the nowel and the other section of the flask placed on the nowel. Sand is filled in the flask-section to 125 make the cope or other part of the mold, and the table is again raised to press the cope and then lowered. The cope-section is then lifted off of the nowel, which exposes the pattern 130

with the drawing-pin projecting upwardly, as shown in Fig. 2. The operator then swings the frame around so as to bring the pattern-drawing sleeve over the pattern and lowers the sleeve by disengaging the spring S from the top of the bearing l of the drawing-sleeve. The sleeve gradually lowers and while lowering is guided by the operator, so that the jaws of the chuck m' engage over the pin on the pattern. The lever O is then swung upwardly to clamp the pin tightly in the jaws of the chuck, after which the operator turns the three-way cock r² sufficiently to admit air to the rapping-cylinder. The rapping immediately commences reciprocating and vibrates the drawing device sufficiently to loosen the pattern in the mold. The valve is then turned farther and air admitted to the drawing-cylinders, which causes the upper cylinder to move upward, carrying the drawing-sleeve upward until the spring S thereon snaps in on the top of the bearing for the drawing-sleeve and holds the latter in its raised position. The pattern is then disengaged from the drawing-rod by swinging the lever O downwardly, as above described. The hole which is made in the mold by the drawing-pin N on the pattern can be stopped before the casting is made, or the projection which is formed on the casting, if the hole is not stopped, can be easily removed from the finished casting.

The machine is especially adapted for quick work whether the molds are formed from single or gated patterns. The patterns are readily provided with a drawing-pin. The mold can be quickly formed and the pattern drawn rapidly and accurately without injuring the mold.

40 The ball-and-socket joint, as described, between the mold-table and the vertically-movable stem carrying the same permits the table to tilt, and in the event of the sand being unevenly placed in the flask, so that it is 45 higher at one side than at the other, when the sand is brought into contact with the pressing-plate the mold-table is caused to tilt, and excessive pressure is not brought to bear on the higher portion of the sand, but the pressure is evenly distributed throughout the flask. When the table is lowered, it is again 50 returned to its horizontal position by the engagement of the joint-socket with the top flat face of the bearing D.

55 We claim as our invention—

1. The combination of a mold-support, a pressing device, a pattern-drawing device adapted to be attached to the pattern and support the same, a support carrying said 60 pressing device and pattern-drawing device, one of said supports being horizontally movable relative to the other to place either the pressing or drawing device in operative position over said mold-support, and means for 65 moving one of said supports vertically toward the other, substantially as set forth.

2. The combination of a mold-support, a

pressing device, a pattern-drawing device adapted to be attached to the pattern and support the same, a frame carrying said pressing device and pattern-drawing device and movable to carry either of said devices into operative position over said mold-support, and means for causing a relative vertical movement of the mold-support and pressing device toward each other, substantially as set forth. 70

3. The combination of a mold-support, a pressing device, a pattern-drawing device adapted to be attached to the pattern and support the same, a frame carrying said pressing device and pattern-drawing device and movable to carry either of said devices into operative position over said mold-support, and means for moving said mold-support toward 85 and from said pressing device, substantially as set forth.

4. The combination of a mold-support, a pressing device, a pattern-drawing device adapted to be attached to the pattern and support the same, a frame carrying said pressing device and pattern-drawing device and movable to carry either of said devices into operative position over said mold-support, and means for causing a relative vertical movement of said mold-support and pattern-drawing device away from each other to draw the pattern from the mold, substantially as set forth. 90

5. The combination of a mold-support, a pressing device, a pattern-drawing device adapted to be attached to the pattern and support the same, a frame carrying said pressing device and pattern-drawing device and movable to carry either of said devices into operative position over said mold-support, and means for raising said pattern-drawing device away from said mold-support to lift the pattern up out of the mold, substantially as set forth. 105

6. The combination of a mold-support, a pressing device, a pattern-drawing device adapted to be attached to the pattern and support the same, a frame carrying said pressing device and pattern-drawing device and mounted to turn about a vertical axis to carry either of said devices into operative position over said support, and means for moving said mold-support vertically toward said pressing device, substantially as set forth. 110

7. The combination of a mold-support, a pressing device, a pattern-drawing device adapted to be attached to the pattern and support the same, a horizontally-movable frame arranged above said mold-support and carrying said pressing device and pattern-drawing device, said frame being movable to carry either of said devices into operative position over said mold-support, means for moving said pattern-drawing device vertically on said frame, and means for moving said mold-support toward and from said pressing device, substantially as set forth. 125

8. The combination of a mold-support, a

pressing device, a pattern - drawing device adapted to be attached to the pattern and support the same, a frame arranged above said mold-support and carrying said pressing device and pattern-drawing device and movable horizontally to carry either of said devices into operative position over said mold-support, means for raising and lowering said mold-support toward and from said pressing device, and fluid-operated means for raising said pattern-drawing device, substantially as set forth.

9. The combination of a mold-support, a pressing device, a pattern - drawing device adapted to be attached to the pattern and support the same, a frame carrying said pressing device and pattern-drawing device and movable to carry either of said devices into operative position over said mold-support, means for raising and lowering said mold-support toward and from said pressing device, means for raising said pattern-drawing device to draw the pattern from the mold, and a rapping device carried by said frame and adapted to rap said frame while said pattern-drawing device is being moved to draw the pattern, substantially as set forth.

10. The combination of a pattern-drawing device provided with means for attaching it to the pattern, means for operating said device to draw the pattern, a rapping device, and a single device which controls the actuating medium for both said operating means for the drawing device and said rapping device, substantially as set forth.

11. The combination of a pattern-drawing device provided with means for attaching it to the pattern, means for operating said drawing device to draw the pattern, a rapping device, and a single device which controls the actuating medium for both said operating means for the drawing device and said rapping device, said controlling device causing the operation of the rapping device before the drawing device commences to draw the pattern, substantially as set forth.

12. The combination of a pattern-drawing device provided with means for attaching it to the pattern, fluid-operated means for moving the pattern-drawing device to draw the

pattern, a fluid-operated rapping device, and a single valve for controlling the fluid to said means for moving the pattern-drawing device and to said rapping device, substantially as set forth.

13. The combination of a drawing-rod provided with jaws adapted to grasp a part secured to the pattern, a part associated with said rod and engaging said jaws, means for causing a relative longitudinal movement between said rod and part whereby said jaws are moved to grasp the pattern, and means for moving said rod to draw the pattern, substantially as set forth.

14. The combination of a drawing-rod provided with jaws adapted to grasp a part secured to the pattern, and having inclined faces, a sleeve surrounding said drawing-rod and engaging said inclined faces of the jaws, means for moving said drawing-rod longitudinally relative to said sleeve whereby said jaws are forced toward each other and grasp the part secured to the pattern, and means for moving said rod to draw the pattern, substantially as set forth.

15. The combination of a drawing-rod provided with jaws adapted to grasp a part secured to the pattern and having outer inclined faces, a sleeve surrounding said drawing-rod and engaging said inclined faces of the jaws, a cam pivoted to the upper end of the rod, a guide-bearing in which said sleeve is vertically movable, and means for raising said sleeve in said bearing, substantially as set forth.

16. The combination of a vertically-movable stem, a mold-table supported and guided by said stem, means for moving said stem, a pressing device arranged opposite to said mold-table, and a universal joint connecting said table and stem so as to permit the table to tilt on the stem, substantially as set forth.

Witness our hands this 3d day of February, 1902.
